UNITED STATES PATENT OFFICE.

MARDIS T. MORTON, OF ARDMORE, OKLAHOMA.

FISHING TOOL.

Application filed November 28, 1925. Serial No. 72,035.

This invention relates to new and useful improvements in well tools, and particularly to tools for removing broken drills from wells.

5 One object of the invention is to provide a device of this character which can be set for the proper engagement with the broken drill, before being lowered into the well.

Another object is to provide a device of 10 this character which includes novel means for forcing the jaws into firm biting engagement with the broken drill, when the device has been lowered into the well.

Another object is to provide means for 15 holding the gripping jaws in proper relation to the broken drill, while the closing mechanism is being operated to force the jaws into gripping engagement with said broken drill.

20 Other objects and advantages will be apparent from the following description when taken in connection with the accompanying drawing.

In the drawing:

25 Figure 1 is a vertical longitudinal sectional view showing the gripping jaws, and operating mechanism thereof, withdrawn into the shell or tube.

30 Figure 2 is a similar sectional view showing the gripping jaws extended into position to engage a broken drill.

Figure 3 is a horizontal sectional view on the line 3—3 of Figure 2.

35 Figure 4 is a vertical longitudinal sectional view on the line 4—4 of Figure 2.

Referring particularly to the accompanying drawing, 10 represents a tubular member which is internally threaded at its upper end, as at 11, for the receptive engagement 40 of a drill stem, and is also internally threaded intermediate its ends, as at 12. Formed in the upper end of the tubular member, inwardly of the threaded portion, is a circular rib 13, against which the upper end of the

45 coil spring 14 bears. Disposed within the tubular member, and engaged with the threads 12, is a disk 15, in which are formed the openings 16 and 17, the former receiving the rods 18 slidably therethrough, while the 50 other openings receive the bolts 19 therethrough. Engaged on the upper ends of the bolts 19, and bearing on the upper face of the disk 15, are the nuts 20, by means of which the said bolts may be adjusted vertically through the openings 17, for a purpose

55 which will presently appear hereinafter.

Each of the bolts 19 is formed with a peripheral flange 21, adjacent its lower end, and encircling each bolt and bearing against the disk 15, and said flange 21, is a coil 60 spring 22. The lower end of the bolt is pivotally connected with the offset end portion 23, of the broken drill gripping jaw member 24. The angle portion of each jaw 24 is pivotally supported on the lower end of a 65 rod 18, to permit said jaw being swung toward and away from the other jaw, upon vertical movement of a bolt 19. In the outer face of each rod 18 there is formed a longitudinally extending recess 25, and engaged 70 with the threads 12 is a ring 26, which lies in said recesses, and limits the longitudinal movement of said rods, in one direction, by engagement of the upper end wall of the recess with the said ring. The upper ends of 75 the rods 18 are permanently connected with the horizontal ring 27, said ring having a V-shaped rib 28, on its upper face for engagement in a similarly shaped groove 29, in the lower face of a ring 30, arranged 80 thereabove. The other end wall of each recess 25 bears against the lower side of the disk 15, to limit the upward movement of the rods. The lower end of the coil spring 14 bears on the upper face of the upper ring 30, and normally tends to urge the rings 27 and 30, together with the rods 18 downwardly, whereby to project the gripping jaws 24 beyond the lower end of the tubular member 10, in position to engage with a 85 broken drill in a well.

Carried by the inner face of the tubular member 10, at a suitable distance above the ring 26, are the spring detents 31, which engage on the upper face of the upper ring 30, 90 upon said ring being forced downwardly by the spring 14, and whereby said ring 30 is held against upward movement.

Disposed through the opposite sides of the tubular member 10, a short distance above the detents 31, and passing into openings 32 in the lower ring 27, are the brass pins 33, which normally hold the jaw operating mechanism withdrawn into the member 10, while the device is being lowered into the 105 well.

The inner vertical faces of the jaws 24 are provided with biting teeth 34, which engage with the broken drill, to draw the same from the well.

When the device is let down into a well, and the ends of the jaws 24 strike the bot-

tom, the weight of the drill stem, in the upper end of the member 10, will be sufficient to force the rings 27 and 30, and rods 18 down to such an extent as to cause the pins 33 to shear off, with the result that upon a slight upward movement of the drill stem and member 10, the spring 14 will project the jaws 24, and their operating mechanism downwardly. The operator then rotates the drill stem, with the result that the member 10 will rotate, causing the disk 15 to be screwed upwardly within the member 10. As the disk moves upwardly it engages with the nuts 20 causing said bolts to be lifted and the jaws to be swung into firm gripping engagement with the broken tool, in the well. The operator then withdraws the entire device from the well, together with the broken drill clamped between the jaws 24.

20 When the mechanism drops downwardly in the tubular member 10, it falls below the detents 31, being urged by the spring 14, and any tendency toward resuming its upper position is prevented by the detents, which engage with the ring 30.

What is claimed is:

1. A drill fishing tool including a rotatable carrier, a member engaged within the carrier and movable longitudinally thereof upon rotation of the carrier, gripping jaws associated with said member, frangible means for temporarily retaining the jaws within the carrier, means for projecting the jaws from the carrier upon breaking of the frangible means, and means operable by said member for moving the jaws into object gripping position upon rotation of the carrier.
2. A drill fishing tool including a rotatable carrier, a member engaged in the carrier and movable longitudinally thereof upon rotation of the latter, gripping jaws

disposed within the carrier, means pivotally supporting the jaws and slidably through said member, frangible means for holding the supporting means, means for projecting the supporting means to extend the jaws outwardly of the carrier upon breaking of the frangible means, and means movably connected to the jaws, slidably through said member, and engaged by said member to move the jaws into gripping position upon rotation of the carrier and movement of said member.

3. A drill fishing device including a rotatable carrier threaded internally, a disk in the carrier and engaged with the threads for movement longitudinally upon rotation of the carrier, rods slidably through the disk, jaws movably supported on the rods, and means connected with the jaws and with the disk whereby said jaws will be moved into gripping position upon rotation of the carrier and movement of said disk.

4. A drill fishing device including a rotatable carrier threaded internally, a disk in the carrier and engaged with the threads thereof for movement longitudinally upon rotation of the carrier, rods slidably through the disk, gripping jaws pivotally carried by the rods, frangible means for temporarily holding the rods at a certain position within the carrier, means for projecting the gripping means beyond the carrier, means for limiting the projecting movement of the gripping means, means for preventing returning movement of the gripping means into the carrier, and means connected with the gripping jaws and movable by the disk for moving the jaws into gripping position.

In testimony whereof, I affix my signature.

MARDIS T. MORTON.
